UNITED STATES PATENT OFFICE.

LEWIS A. SAFFORD, OF BUFFALO, NEW YORK, ASSIGNOR TO BARCALO MANUFACTURING COMPANY, OF BUFFALO, NEW YORK.

DESIGN FOR A HANDLE FOR WRENCH OR SIMILAR HAND-TOOLS.

57,153.

Specification for Design.

Patented Feb. 22, 1921.

Application filed November 26, 1920. Serial No. 426,657. Term of patent 14 years.

To all whom it may concern:

Be it known that I, LEWIS A. SAFFORD, a citizen of the United States, residing at Buffalo, in the county of Erie and State of New York, have invented a new, original, and ornamental Design for a Handle for Wrenches or Similar Hand-Tools, of which the following is a specification, reference being had to the accompanying drawing, forming a part thereof.

In the accompanying drawings:

Figure 1 is a side elevation, and

Fig. 2 is an edge elevation of a wrench having a handle embodying my new design.

The handle is provided in its side faces with depressions forming elongated, sunken

panels disposed end to end lengthwise of the handle, and surrounded by narrow, marginal, raised portions which extend along the side edges of the panel and around the end of the handle. Said raised, marginal portions of the side face are bright or polished while the faces of the sunken panels are dull and the opposite longitudinal edges of the handle are knurled or roughened.

I claim:

The ornamental design for a handle for a wrench or similar hand tools, substantially as shown and described.

Buffalo, N. Y., Nov. 19, 1920.

LEWIS A. SAFFORD.
